UNITED STATES PATENT OFFICE.

JESSE G. VINCENT, OF DETROIT, MICHIGAN, ASSIGNOR TO PACKARD MOTOR CAR COMPANY, OF DETROIT, MICHIGAN, A CORPORATION OF MICHIGAN.

HYDROCARBON-MOTOR.

1,305,037.

Specification of Letters Patent. Patented May 27, 1919.

Application filed August 30, 1916. Serial No. 117,774.

To all whom it may concern:

Be it known that I, JESSE G. VINCENT, a citizen of the United States, and resident of Detroit, Wayne county, State of Michigan, have invented certain new and useful Improvements in Hydrocarbon-Motors, of which the following is a specification.

This invention relates to hydrocarbon motors and particularly to means for supplying fuel thereto.

In the use of hydrocarbon motors on motor vehicles and otherwise, it is frequently necessary to arrange the main fuel supply tank at a point lower than the motor carbureter, whereby it becomes necessary to provide means, preferably operated by the motor, for drawing or forcing the gasolene or the fuel from the main supply tank to the carbureter. One well known means for raising the gasolene from the main tank to a smaller receptacle above the carbureter from which it may be fed to the carbureter by gravity, is a vacuum operated device in which the vacuum is supplied by the intake chamber of the motor. It has been found, however, that when this vacuum supply is depended upon to raise the gasolene to a higher level the device sometimes fails if the motor is operated with wide open throttle continuously for some length of time. Under such conditions the vacuum in the intake chamber drops very materially and is therefore not sufficient under some conditions to operate the device above referred to. If instead of using the vacuum in the intake chamber as above suggested, a vacuum pump is used to operate the device for raising the level of the gasolene, it will be found necessary, in motor vehicle use, to supply a hand operated pump also in order to raise the gasolene for starting the motor.

One of the objects of the present invention is to provide a vacuum operated device of the above description, with connections both to the motor intake chamber and to a motor operated vacuum pump whereby a suitable vacuum is always obtainable, the pump supplying the vacuum when the vacuum in the intake chamber falls below a given point and the intake chamber quickly supplying a vacuum for operating the device when the motor is being turned over or cranked by hand or by the usual electric cranking device.

Another object of the invention is to pro-

vide a pump and valve unit of novel construction and arrangement.

Other objects of the invention will appear from the following description taken in connection with the drawings which form a part of this specification, and in which:

Figure 1 is a view showing part of a hydrocarbon motor adapted for motor vehicle use, together with a vacuum operated device and connections, all of which go to illustrate one form of the invention.

Fig. 2 is an enlarged longitudinal sectional view of the pump and valve mechanism shown in Fig. 1, with the pump in a different position;

Fig. 3 is a transverse section on the line 3-3 of Fig. 2;

Fig. 4 is a section on the line 4-4 of Fig. 2; and

Fig. 5 is an edge view of the disk used to form a dividing wall in the pump barrel.

Referring to the drawings, 10 represents generally a vacuum operated device of well known form, many of which are in general use on motor vehicles for raising the gasolene in the main supply tank to a higher level above the motor carbureter, so that the gasolene may be fed by gravity from said device to the carbureter. The device and its operation will be briefly described.

The device 10 is in the form of upper and lower tanks 11 and 12 respectively, a pipe 13 having a flap valve 14 connecting the bottom of the upper compartment with the lower compartment. There is an outlet pipe 15 which leads from the lower compartment to the motor carbureter.

The upper compartment contains a float 16 which is connected to a lever 17 pivoted at 18 to an arm 19 extending downwardly into the compartment. The gasolene intake port is shown at 20. A lever 22 connected by a link 23 with the lever 17 above described, is pivoted at 24 as is also another lever 25, to which are connected a valve 26 which controls the vacuum port 27 and a valve 28 which controls the vent 29. This vent 29 opens into the upper compartment as shown and it is also connected to the lower compartment 12 by a pipe 30. A spring 31 has its ends so connected to the levers 22 and 25 that a toggle action of these levers is obtained. Thus the spring yieldingly holds both of the levers 22 and 25 in the upper position in which they are shown

in full lines in Fig. 1, and when they are in this position the vacuum port 27 is closed and the vent 29 is open. When the valves are in these positions the gasoline in the 5 upper compartment 11 flows freely through the pipe 13 into the lower compartment 12. This of course causes the float 16 to drop and through the lever 17 and link 23 it pulls the lever 22 down with it, thereby opening the 10 port 27 and closing the vent 29. Thus the vacuum port being open and the vent 29 closed the flap valve 14 will be closed and the gasoline will be drawn into the upper compartment through the port 29. As the 15 upper compartment 11 fills up with gasoline the float 16 will be raised to the position in which it is shown in full lines in Fig. 1 and the operation will be repeated as long as air is exhausted through the port 27 and the 20 gasoline is withdrawn from the lower compartment 12.

In the drawings, the vacuum operated device above described is connected to a hydro-carbon motor 32 of the well known V-type. This motor comprises the usual crank shaft 33, connecting rods 34, cylinders 35, cam shaft 36 driven from the crank shaft, intake header or chamber 37, and carburetor 38. The outlet pipe 15 from the lower compartment 12 of the device 10 is shown as connected to the carburetor 38 in the usual way.

Secured to one side of the motor 32 is a vacuum pump 39 which has an eccentric or 35 crank shaft 40 driven from the cam shaft 36 as by a pair of spiral gears 41.

This vacuum pump 39 is of novel construction and it combines with it or has formed as a part of it a valve which is arranged in the connection between the motor intake chamber 37 and the vacuum operated device 10. The said connection comprises the pipes 42 and 43, the former of which runs from the intake chamber 37 to the pump 39 and the latter of which runs from the device 10 to said pump. The pipe 43 is connected to the device 10 at the vacuum port 27, as shown clearly in Fig. 1.

The barrel of the pump 39 is drilled with 50 a through bore, the lower part of which forms the cylinder of the pump and the upper part of which forms a valve chamber 44. The pump cylinder is divided from the valve chamber by an imperforate wall 55 formed by a disk 45 expanded into an annular groove 46 in the pump barrel intermediate of its ends. An edge view of this disk 45 is shown in Fig. 5 and it will be seen that in its original form it is substantially concavo-convex. It is expanded into the groove 46 by hammer blows which straighten it out as shown in Fig. 2.

A trunk piston 47 is arranged to travel in the pump cylinder and is operated by a connecting rod 48 and the eccentric 40. The

piston is formed with an annular groove 49 which registers with an intake port 50 at one end of its stroke as shown in Fig. 2, and with an outlet port 51 at the other end of its stroke as shown in Fig. 1. A series of radial openings 52 connect the interior of the piston and of the cylinder with the groove 49. It is believed that the operation of this vacuum pump will be obvious from the above description. The intake port 50 is connected with the pipe 43 so that the pump will operate to create a vacuum or partial vacuum in the upper compartment of the device 10. 70 75

A valve 53 is arranged in the chamber 44 and is spring pressed to its lower or closed position as by a spring 54. This valve has side walls formed with a groove 55 which registers with the port 56 only when the valve is in its raised position. Openings 57 extend from the groove 55 to the interior of the valve. The port 56 is connected by a channel 58 with the pipe 43 as shown in Figs. 1 and 2. The pipe 42 is connected to the upper part of the valve chamber 44 above the valve 53 so that the vacuum in the intake chamber 37 will tend to raise the valve 53 against the spring 54 to the position in which it is shown in Fig. 2. When the vacuum releases the valve 53 it falls to the position shown in Fig. 1. 80 85 90 95

From the above description it will be seen that the valve 53 is in the pipe connection between the vacuum operated device 10 and the intake chamber 37 and that this valve is affected only by the vacuum or pressure on the intake chamber side of said valve, the vacuum or pressure on the other side of the valve having no tendency to change the position of the valve in any way. 100

If the motor has been standing and there is not sufficient gasoline in the compartment 12 of the device 10 to start it, the motor will be cranked with the throttle valve partly or practically closed and a high vacuum will at once be formed in the intake chamber 37 which will immediately raise the valve 53 to the position in which it is shown in Fig. 2, thereby opening communication between the pipes 42 and 43. This vacuum will immediately draw the gasoline from the main supply tank 59 through the pipe 60 and port 20 to the upper compartment 11 of the device 10. As soon as said upper compartment is filled the float and levers in said device will have moved from the position in which they are shown in dotted lines to the position in which they are shown in full lines in Fig. 1 and the gasoline in the upper compartment will flow into the lower compartment, from which latter compartment it would be fed by gravity to the carburetor 38. Of course, the vacuum pump 39 will also be operated by the motor, but when the latter is turning over very slowly the capacity of the pump 110 115 120 125 130

39 will be very limited, whereas the relatively large pistons of the motor will create a considerable vacuum in the intake chamber 37. After the motor starts however both the vacuum pump 39 and the intake chamber 37 will act simultaneously under ordinary conditions to operate the device 10. If the motor throttle is now closed or nearly so, with the motor still running, the vacuum 10 will be raised in the chamber 37 and that vacuum will be largely used to operate the device 10. On the other hand, if the motor is run for any length of time with wide open throttle, and particularly if under heavy 15 load and fairly good speed so that considerable gasoline is used, the vacuum in the chamber 37 will be inadequate to operate the device 10, but the vacuum pump 39 will take up the work and continue to keep the carburetor supplied with sufficient fuel. When 20 the vacuum pump is thus called upon to do the greater part of the work the valve 53 is closed so that the action of the pump will not be interfered with by the relatively low 25 vacuum in the intake chamber 37, and likewise the operation of the pump will not affect the functioning of the motor by reducing the vacuum in the intake chamber.

It will be understood that other forms of 30 the invention and various changes and alterations may be made, within the scope of the claims, without departing from the invention.

Having thus described my invention, what 35 I claim and desire to secure by Letters Patent is:—

1. The combination with a hydrocarbon motor having a carburetor and intake chamber, of a vacuum operated device for supplying gasoline to the carburetor, a vacuum pump connected to the motor to be continuously operated thereby, means for communicating the pump and intake chamber with the vacuum operated device, and means operated by a predetermined vacuum in the intake chamber for opening the communication between the intake chamber and the vacuum operated device.

2. The combination with a hydrocarbon motor having a carburetor and intake chamber, of a vacuum operated device for supplying gasoline to the carburetor, a vacuum pump connected to the motor to be continuously operated thereby, means for communicating the pump and intake chamber with the vacuum operated device, and a valve operated by a predetermined vacuum in the intake chamber for opening the communication between the intake chamber and the vacuum operated device. 50 55 60

3. The combination with a hydrocarbon motor having a carburetor and an intake chamber, of a vacuum operated device for supplying gasoline to the carburetor, a connection from said device to the intake chamber, and a valve in said connection operated by the vacuum on the chamber side of said valve and regardless of the vacuum or pressure in the connection on the other side of 65 70 75 said valve.

4. The combination with a hydrocarbon motor having a carburetor and an intake chamber, of a vacuum operated device for supplying fuel to the carburetor, a pipe from said device to the intake chamber, and a valve in said pipe held yieldingly in closed position and adapted to be opened by vacuum in the intake chamber said valve being unaffected by the degree of vacuum or pressure in the pipe on the other side of the 80 valve.

5. A pump and valve construction comprising a barrel having an intermediate dividing wall, a pump piston operating in the barrel at one side of the wall, and a piston 85 valve operating in the barrel at the other side of said wall.

6. A pump and valve construction comprising a barrel having a through bore, said barrel having an interior annular groove 90 intermediate its ends, a disk expanded into said groove to form a dividing wall for said barrel, and pistons arranged in said barrel on either side of said wall.

In testimony whereof I affix my signature. 95
JESSE G. VINCENT.
